W. A. FRASER
FLUSHING SYSTEM.

APPLICATION FILED NOV. 29, 1912. RENEWED MAY 15, 1914.

1,110,620.

Patented Sept. 15, 1914.

FIG. 1.

UNITED STATES PATENT OFFICE.

WILLIAM ALEXANDER FRASER, OF GEORGETOWN, ONTARIO, CANADA.

FLUSHING SYSTEM.

1,110,620.

Specification of Letters Patent. Patented Sept. 15, 1914.

Application filed November 29, 1912, Serial No. 734,026. Renewed May 15, 1914. Serial No. 838,667.

To all whom it may concern:

Be it known that I, WILLIAM ALEXANDER FRASER, of the town of Georgetown, in the county of Halton, in the Province of Ontario, Canada, have invented certain new and useful Improvements in Flushing Systems, of which the following is the specification.

My invention relates to improvements in a sanitary device for flushing systems and particularly relates to a patent granted by the United States Patent Office under No. 1,062,148 on May 20th, 1913, and the object of the present invention is to improve the construction of the sanitary device therein shown, and divided out of the case.

My invention consists of a sanitary device connected by a pipe to the tank near the bottom and provided with a soluble antiseptic disinfecting substance, a pipe connecting the device to the flushing pipe and a removable valve support and valve located below the bottom of the sanitary device from which the pipe extends into the tank and from 25 which the pipe extends into the flushing pipe, the parts being otherwise constructed and arranged as hereinafter more particularly explained.

Figure 1, is an elevation showing a flushing tank provided with my sanitary device which is shown in section. Fig. 2, is a vertical section through the sanitary device at right angles to the section of the sanitary device shown in Fig. 1. Fig. 3, is a plan view of the sanitary device. Fig. 4, is a perspective detail of the valve support for the device. Fig. 5, is a perspective detail of the valve. Fig. 6, is a section of the valve.

In the drawings like letters of reference indicate corresponding parts in each figure.

A is my flushing tank, the interior construction of which forms the subject matter of a separate application bearing even date herewith.

B is the sanitary device consisting preferably of a base B', a glass or transparent cylindrical portion B² fitting within the annular flange B³ of the base and a top B⁴ having a depending flange B⁵ surrounding the top 50 of the glass cylinder. The base B' is provided with a reduced extension B⁶ internally threaded at the bottom and connected by a pipe C to the tank near the bottom.

B⁷ is an upwardly extending flange externally threaded and forming a central opening or orifice at the top of the receptacle.

B⁸ is a cap, which is interiorly threaded and provided with a cork or other disk B⁹ to make it liquid tight in a manner, which is commonly known. 60

B¹⁰ is a flanged central orifice in the base B' in which is inserted a tube B¹¹ provided with slots B¹² near the top.

D is a set screw, which extends into the threaded top of the tube B¹¹ and is designed 65 to regulate the size of the orifice B¹² and thereby regulate the flow of the liquid through the same into the receptacle outside of the tube B¹¹. The receptacle is intended to be filled with any sanitary soluble anti-septic disinfecting substance either in disk, 70 granulated or other suitable form.

E is a pipe leading from the base B' into the flushing pipe F and closet and is provided with a perforated cap E' to prevent 75 the ingress of foreign matter.

G is the removable seat for the valve H controlling the supply of the sanitary disinfecting liquid. The seat G is provided with a flange G', a nut-shaped bottom G², 80 a portion G³, which is screwed into the interior of the extension B⁶ and the seat proper G⁴ having a central orifice G⁵ and supported by legs G⁶, which leave openings G⁷ through which the liquid may pass 85 freely, such openings being opposite the pipe C. The valve H is provided with depending legs H', a central orifice H², a disk H³ made of rubber or other suitable material of a somewhat soft nature and is 90 also provided with a depending portion H⁴ extending through the orifice H² and through which extends a pin H⁵ of sufficient length, so as to hold the disk H³ in place (see Fig. 6). The bottom B' and 95 top B⁴ are held together by suitable bolts 2 extending through lugs formed on the top and bottom as indicated in Figs. 1 and 3.

The operation of my sanitary device is 100 as follows. The receptacle, which is filled as hereinbefore described with a suitable disinfecting substance is formed as described. When the tank has been emptied in flushing the valve H drops and the water 105 as the tank is being refilled passes through the pipe C into the bottom chamber of the receptacle around the valve H and up through the tube B¹¹ and through the orifice B¹² and out into the receptacle on to 110 the disinfecting substance where the water is permeated with such substance and passes

down through the perforated cap E' and pipe E into the flushing pipe F. When the pressure rises in the tank sufficiently the valve H is raised, so as to form its seat on the bottom of the tube B¹¹ and thereby cut off the supply of the reflush water, which is permeated with the disinfecting liquid. The permeated water can, of course, be arranged to be in sufficient quantities, so as to reflush the bowl and preserve it in a sanitary condition.

What I claim as my invention is.

1. In a sanitary device, the combination with the tank and flushing pipe, of a sanitary device for the re-flush water comprising a pipe extending into the tank near the bottom, a base suitably connected to the pipe and provided with a chamber, a pipe leading from below the base to the flushing pipe, a central tube leading from below the chamber upwardly and provided with an orifice in the top, a valve located at the bottom of the tube and above the level of the pipe leading into the bottom of the tank, a casing extending upwardly from the base and a cover for the casing, as and for the purpose specified.
2. In a sanitary device, a tank, a flushing pipe a receptacle comprising a base provided with a downwardly extending portion forming a chamber, a pipe leading from said chamber into the bottom of the tank, a pipe leading from above the base into the flushing pipe, a central tube leading from the chamber below the base upwardly and provided with an orifice at the top, a casing located on the base and a suitable top for the casing and a valve located beneath the central tube as and for the purpose specified.

3. In a sanitary device, a tank, a flushing pipe a receptacle comprising a base provided with a downwardly extending portion forming a chamber, a pipe leading from said chamber into the bottom of the tank, a pipe leading from above the base into the flushing pipe, a central tube leading from the chamber below the base upwardly and provided with slots near the top, a set screw fitting into the top of the tube and designed to regulate the side of the slots a casing and a suitable top for the casing and a valve located beneath the central tube as and for the purpose specified.

4. In a sanitary device, a tank, a flushing pipe a receptacle comprising a base provided with a downwardly extending portion forming a chamber, a tube leading from said chamber into the bottom of the tank, a pipe leading from above the base into the flushing pipe, a central tube leading from the chamber below the base upwardly and provided with an orifice at the top, a casing located on the base, a suitable top for the casing, a disk valve provided with suitable legs, a valve support provided with a threaded portion fitting into the bottom of the extension of the boss forming the chamber and having upwardly extending legs forming circumferential openings designed to be located on a level with the pipe leading into the tank and having an annular top upon which the valve normally rests as and for the purpose specified.

WILLIAM ALEXANDER FRASER.
